associates

Appell and Noble, of the same place.

Letters Patent No. 152297 - Dated Feb. 27 - 1866. Entitled *Design for the Plates of a Store*

The schedule referred to in these letters, Patent and making part of the same

shall where it may concern.

Be it known that we, G. Smith and Mr. Brown, of Philadelphia, County of Philadelphia, State of Pennsylvania, have invented or produced a new and original design for the plates of the "National Range," and we do hereby declare the accompanying drawing with the following explanation of the same to form a full, clear and exact description of the said design:

In the accompanying drawing

Fig. 1 represents the front plate of the "National Range," and
Fig. 2, one of the side plates.

At the side edges of the front plate is an ornamental moulding, and near one end of the plate is a panel B, which is enclosed by an ornamental moulding L.

On the panel B are hung two doors C, each of which is edged with a plain moulding, and in the centre of the door is an ornamental figure of the person shown in the drawing.

Each of the oven doors is edged with a plain moulding, and has in the centre an ornamental figure similar to that on the doors C.

DES. 2270

2

On the plate above the over doors there is a series of ornamental figures of the four seasons in the drawing, and below the side doors are the four national range.

On the side plate there is a panel which has a wide ornamental moulding, and in which is a smaller panel, which has a similar moulding, and in the centre of the latter panel is an ornamental figure similar to that on the door.

At the upper edge of the plate, is a series of ornamental figures of the characters shown in the drawing.

Verlaine

The design for the plates of the national range substantially as shown in and by the accompanying drawing.

Contractors where we have signed documents to this specification in the presence of two subscribing witnesses.
